(57) CLAIM

The ornamental design for a vaporizing pipe in gas chromatography, as shown and described.

DESCRIPTION

FIG. 1 is a front view of the vaporizing pipe in gas chromatography, the back view being a mirror image thereof;

FIG. 2 is a left side view thereof;

FIG. 3 is a right side view thereof;

FIG. 4 is a plan view thereof;

FIG. 5 is a bottom view thereof;

FIG. 6 is a perspective view thereof; and,

FIG. 7 is a back perspective view thereof.
